(57) **CLAIM**

I claim the ornamental design for a front ledge area for a refrigerated display case, as shown and described.

DESCRIPTION

FIG. 1 is a perspective view of a front ledge area for a refrigerated display case.

FIG. 2 is a top view of the front ledge area for a refrigerated display case of FIG. 1; and,

FIG. 3 is an enlarged perspective view of a portion of the front ledge area for a refrigerated display case of FIG. 1.

The broken lines showing of the environment are for illustrative purposes only and form no part of the claimed design. The boundary lines showing the boundary between the claimed design and the unclaimed portions of the design are for illustrative purposes only and form no part of the claimed design. The boundary lines are represented by alternating dashes and dots.
